MERCHANTISE WRAPPER

Oscar Horowitz, New Rochelle, N. Y.

Application March 14, 1933. Serial No. 660,727

3 Claims. (Cl. 229—87)

This invention relates to improvements in merchandise receptacles or wrappers and has more particular relation to improvements in shirt holders or protectors, preferably constructed of transparent material such as the so-called "Cellophane."

The principal object of the invention is to provide a transparent protector, but at the same time allow for a sight and touch inspection of the article wrapped.

A further object of the invention is to provide a transparent shirt protector with a sight inspection opening so located in relation to the shirt that the fingers may be introduced to grasp both back and front a single thickness of the material of which the shirt is fabricated.

In the accompanying drawing forming part of this specification,

Figure 1 represents a back plan view of a man's shirt folded and wrapped in "Cellophane" with the sight and touch opening for inspection therein,

Figure 2 represents an end elevation, partly in section, illustrating the human fingers introduced through the inspection opening for both sight and touch inspection.

Previously it has been common practice to wrap a great many articles in "Cellophane" to protect them against damage or soiling and at the same time allow a so-called inspection of the articles so wrapped. However, many of these wrappers, especially such wrappers as enclosed men's shirts or other fine fabrics, have been so applied to the shirts as to preclude any possibility of a real examination or inspection being made of the shirt without first removing the wrapper. This practice has led to the foisting on the public of inferior grades of material for the reason that the lower grades of material when inspected through the very brilliant "Cellophane", have the appearance of high grade materials, and the real materials of quality are thus handicapped as they, when inspected through the "Cellophane", do not indicate a greater quality than that indicated by the very poorest materials.

In testing the quality of fabrics, the customer invariably wishes to feel its thickness or weight and to visually inspect it as to its quality by noting its silky appearance or the density of the weaving or the flexibility or stiffness.

Many materials of a cheaper nature are apparently given permanent weight by being "loaded" with substances that apparently impart weight but which are ordinarily removed after

the material has been through the laundry. Such subterfuges for giving cheap materials the look of expensive materials cannot be detected when viewed through the polished "Cellophane" surface. In fact, such "Cellophane" entirely precludes the inspection of the material as to its sheen or silky appearance, which as far as broad-cloth is concerned, is an accompaniment of quality, the cheaper broadcloths having no sheen whatever but a dull cotton look. A cheap shirt when viewed through the "Cellophane" has the same silky look that a real piece of quality broadcloth would have in the same situation.

The objection of many customers in buying articles completely enclosed in "Cellophane" has now reached a point where such customers refuse to buy unless the package is broken in such a way as to give them a chance to feel and inspect the fabric. The great advantage of inspecting material of a shirt has reached a point where the present applicant has just closed one order of 120,000 shirts enclosed in this apertured "Cellophane" wrapper. This order was closed principally on account of the fact that these high grade shirts were enclosed in such manner that they could be completely inspected by the customer without disturbing the wrapper.

The relative arrangement of the wrapper with its inspection opening and the shirt is such that if the portion of the shirt under the inspection opening should become slightly soiled by repeated handlings, this will occupy a position on the shirt that would not show when the shirt was worn.

By reference to Figure 1 it will be seen that the shirt is folded into a parcel with the front covered by an unbroken front portion 21 of the "Cellophane" wrapper. This completely protects the front of the shirt from any soiling, moisture or the like. The shirt is so doubled before being enclosed in "Cellophane" as to bring the open front 20 of the same up the back. This is for the specific purpose of bringing the lower portion of the open front of the shirt which lies below the normal waistline of the wearer into a position to be viewed and inspected through the triangular opening 12 formed by the peculiar folding of the side flaps 22 and the end flaps 23 of the "Cellophane." These side flaps and end flaps are formed integral with the material of the front 21. The side flaps, in order to have a double thickness bounding the opening 12 are doubled back upon themselves as at 13 and 14 forming internal flaps 13' and 14'. This gives a double thickness with a double edge to

the two sides of the triangular opening 12 and effectively prevents any tearing by constant inspection through the openings, as it is a well known fact that it is almost next to impossible 5 to tear the double edge of "Cellophane" at least by ordinary pressure. The top double edge 15 of the upper end flap 23 bounds the upper edge of the triangular opening and thus completes the double thickness doubled edge wall of the 10 entire opening. To effect this result, the top end flap 23 is doubled over in a fold at 25 and extends down over the upper end of the side flaps 22 as at 26 and 27, the triangular flap 15' being arranged between the two lines 26 and 27.

15 In order that the adjoining parts of the flaps 22 and 23 may be secured together, seals 18 and 19 are adhesively secured to the same at the points of intersection of these flaps, a seal 17 securing the two flaps 22 together where they 20 overlap. The lower flap 23 extends up over the two side flaps as at 29 and is also secured in position by the seal 17.

It will be seen from the above that the triangular area 12 is entirely surrounded by double 25 "Cellophane" edges so that any stretching or disarrangement of the edges of this opening will not be liable to tear the "Cellophane" as would be the case where the triangular opening is bounded by a raw edge of the "Cellophane."

30 By reference to Figure 2 it will be seen how the fingers may be passed through the opening 12 under the front flap 20 of the shirt and under the single thickness 10 of the shirt so that this single thickness may be pressed and 35 felt between the fingers to gauge its thickness and to detect, if present, the weight adding fillers put in cheap materials. Further, by turning over the shirt, the customer may easily examine the sheen or silky appearance of the 40 fabric in determining its quality. This is especially true of broadcloth of which shirts are mostly constructed.

It will be seen from the foregoing that while the merchandise is fully protected in a "Cello- 45 phane" wrapper by applicant's invention, the

greatest drawback to such an enclosure has been obviated and the customer is enabled at any time to inspect through the wide opening 12 and to feel with his fingers to determine the quality, actual color, and other conditions of the material of which the shirt is manufactured. The inventor has thus obviated a very serious objection to the present "Cellophane" enclosure for shirts which precludes any possibility of the customer examining either by sight or touch the article he is buying except by looking through the "Cellophane". In so examining the article through the "Cellophane", he is often misled as to its quality, the highly finished surface of the "Cellophane" hiding the lack-lustre and other cotton characteristics of the fabric, and he is only aware of the cheap quality shirt that he has purchased after he removes the "Cellophane".

This is not a theoretical situation, but such deception is going on every day in completely enclosed cellophane wrapped merchandise.

What I claim is:

1. In a "Cellophane" wrapper for shirts, the combination with side and end flaps so doubled 100 as to leave an inspection opening bounded by doubled edges, of sealing means for securing the end and side flaps together.

2. In a "Cellophane" wrapper for shirts, the combination with an unbroken front portion, of 105 back, side and end flaps so formed as to leave an inspection opening having double walls, and securing means for fastening the side and end flaps together to form said opening.

3. Wrapper for shirts comprising a sheet of 110 transparent material folded to define a flat shirt receiving envelope, the lines of fold bringing the free edges of said shirt to one side of said envelope, the free edges of contiguous portions of said sheet being arranged to define an 115 inspection opening, and means for securing adjacent contiguous portions together adjacent the meeting points of the free edges which bound said opening.
